(57) **CLAIM**

I claim the ornamental design for deep fryer with warming tray, as shown and described.

DESCRIPTION

FIG. 1 is a front view of a deep fryer with warming tray according to an embodiment of the invention.

FIG. 2 is a right side view of the deep fryer with warming tray depicted in FIG. 1.

FIG. 3 is a rear view of the deep fryer with warming tray depicted in FIG. 1.

FIG. 4 is a left side view of the deep fryer with warming tray depicted in FIG. 1.

FIG. 5 is a top view of the deep fryer with warming tray depicted in FIG. 1.

FIG. 6 is a bottom view of the deep fryer with warming tray depicted in FIG. 1.

FIG. 7 is a front, right side perspective view of the deep fryer with warming tray depicted in FIG. 1.

FIG. 8 is a right side view of the deep fryer with warming tray depicted in FIG. 1 with a partially open warming tray.

FIG. 9 is a left side view of the deep fryer with warming tray depicted in FIG. 1 with a partially open warming tray.

FIG. 10 is a top view of the deep fryer with warming tray depicted in FIG. 1 with a partially open warming tray.

FIG. 11 is a bottom view of the deep fryer with warming tray depicted in FIG. 1 with a partially open warming tray, and,

FIG. 12 is a front, right side perspective view of the deep fryer with warming tray depicted in FIG. 1 with a partially open warming tray.

Items shown in broken lines are for illustrative purposes only and form no part of the claimed invention.

1 Claim, 12 Drawing Sheets
